STEAMING SPOOL

Emerson H. Tompkins, Waterbury, Conn., assignor to Scovill Manufacturing Company, Waterbury, Conn., a corporation of Connecticut

Application April 19, 1934, Serial No. 721,333

5 Claims. (Cl. 242—123)

This invention relates to spools, and more particularly to a sheet metal spool adapted for use in the steaming and soaking of spooled material, such as silk, for use in the manufacture of textiles.

One object of this invention is to provide a metal spool of the above nature having a pair of concentric tubes supported at their ends in a pair of circular end heads, each head comprising a circular lining ring interlocked upon an end disc, said ring being provided with a large central aperture adapted to fit tightly over the end of the outer tube or drum of the spool, thus producing a sharp right-angle junction between the lining ring and the outer drum without the use of solder as a fillet.

A further object is to provide a spool of the above nature in which the outer discs of the end heads are provided with a plurality of spaced lugs inturned from the body of the disc and radially arranged with respect to the axis of the spool, the outer edges of said inturned lugs having a tight engagement within the ends of the outer drum for reinforcing said drum against external crushing stresses.

A further object is to provide a spool of the above nature which will be simple and strong in construction, inexpensive to manufacture, easy to assemble and manipulate, compact, ornamental in appearance, and very efficient and durable in use.

With these and other objects in view, there has been illustrated on the accompanying drawing, one form in which the invention may be conveniently embodied in practice.

In the drawing:

Fig. 1 represents a side elevation of the improved winding spool.

Fig. 2 is an end view of the same.

Fig. 3 is a longitudinal sectional view on a slightly enlarged scale, the view being taken along the dotted line 3—3 of Fig. 2, looking in the direction of the arrows.

Fig. 4 is a transverse sectional view, taken along the line 4—4 of Fig. 3, looking in the direction of the arrows.

This invention is an improvement over an application filed by Frederick R. Reutter, Serial No. 697,605, November 11, 1933, and owned by the same assignee.

Referring now to the drawing in which like reference numerals denote corresponding parts throughout the several views, the numeral 10 generally indicates a metal winding spool embodying the invention, said spool consisting of an outer cylindrical shell or barrel 11, a pair of

transverse end heads or flanges 12 and 13, and an inner concentric spindle tube 14. The outer shell or barrel 11 is formed from a single piece of sheet metal bent into cylindrical shape and having its side edges provided with a pair of inturned longitudinal abutting parallel flanges 15, the outer junction seam of which is adapted to be filled with a line of solder 15a to provide a smooth flush surface.

The heads 12 and 13 are identical in construction and each comprises an exterior disc 16 and an interior flat lining plate or ring 17. The exterior disc 16 is offset outwardly at its central portion to form an annular boss 18. The center of the boss 18 is apertured and bent inwardly to form a curved flange or hub 19, against which the ends of the spindle 14 are adapted to be spun over, as shown in Fig. 3. The aperture in the lining ring 17 is of such size that the ring will slip over the ends of the barrel 11 and have a substantially snug fit thereupon.

In order to affix the lining ring 17 to the disc 16, the peripheral section of said ring 17 is curled over outwardly upon itself to form a round bead 20 which is adapted to embrace the outer edge 25 of said disc 16 in the manner shown in Fig. 3. The above construction not only forms a permanent fastening means between the ring 17 and the disc 16 to form the head units 12 and 13, but also reinforces the strength and stiffness of said heads. It also produces smooth round edges for said heads 12 and 13 over which the yarn or silk being wound upon the spool may easily slide without catching. It will be noted that the outside surface of the beads 20 lie in substantially the same plane as the central bosses 18, so that the spool will have a stable support when resting on a horizontal surface, this construction also permitting the spools to be readily stacked.

The lining ring 17 and the disc 16 having been 40 assembled as above described to form the unit heads 12 and 13, said heads will next be positioned on the opposite ends of the outer barrel 11, and, as shown in Fig. 3, held in permanently attached position by spinning the ends 21 of the 45 spindle tube 14 outwardly around the hubs 19, 19, as described above.

In order to further strengthen the construction of the spool and increase the resistance of the barrel 11 to inward collapsing forces, such as 50 might be caused by an excessive shrinkage of the material wound upon the spool when drying, the end discs 16, 16 are provided with a plurality of substantially broad integral inwardly extending flat lugs 22 struck inwardly from the body of the 55

disc 16 and leaving a corresponding number of openings 23 therein.

The lugs 22 are preferably equally spaced in a circular formation around the axis of the spool 5 and are radially positioned with respect to said axis in such a manner that the outer horizontal edges of said lugs are adapted to tightly engage with the inside of the barrel 11. The noses or inner extremities 24 of the lugs 22 are preferably 10 rounded so as to act in the manner of a cam for assisting in concentrically assembling the end heads 12 and 13 upon the respective ends of the barrel 11.

The barrel 11 and the lining ring 17 are preferably made from stainless steel so as to avoid the 15 possibility of discoloring or otherwise injuring the yarn or other material that may be wound upon the spool 18. The barrel 11 is provided with a plurality of rows of spaced apertures 25 for 20 permitting the yarn on the spool to be freely exposed to the action of the steam or other fluid to which it is to be subjected. The steam is adapted to pass into the interior chamber of the spool through the openings 23 in the end discs 16, and 25 also through an aperture 26 in the interior of the spindle tube 14.

While there has been disclosed in this specification one form in which the invention may be embodied, it is to be understood that this form is 30 shown for the purpose of illustration only, and that the invention is not to be limited to the specific disclosure but may be modified and embodied in various other forms without departing from its spirit. In short, the invention includes 35 all the modifications and embodiments coming within the scope of the following claims.

Having thus fully described the invention, what is claimed as new and for which it is desired to 40 secure Letters Patent, is:

1. In a winding spool, a tubular barrel, a pair of transverse end discs having outwardly offset central bosses to form seats for receiving the opposite ends of said barrel, said bosses having concentric co-axial apertures, a spindle tube engaging 45 in said apertures and connected to said discs for holding the latter in assembled position against the ends of said barrel, said discs having a plurality of spaced longitudinal lugs with their planes 50 radially positioned relative to the axis of said barrel struck inwardly from the body of said bosses, the edges of said lugs engaging said barrel, whereby said lugs will support the interior wall of said barrel against compressive forces.

2. In a winding spool, a tubular barrel, a pair

of transverse end discs having outwardly offset central bosses to form seats for receiving the opposite ends of said barrel, said bosses having concentric co-axial apertures, a spindle tube engaging 5 in said apertures and connected to said discs for holding the latter in assembled position against the ends of said barrel, said discs having a plurality of spaced longitudinal lugs with their planes radially positioned relative to the axis of 10 said barrel struck inwardly from the body of said bosses, the edges of said lugs engaging said barrel, whereby said lugs will support the interior wall of said barrel against compressive forces.

3. In a winding spool, a tubular barrel, a pair 15 of transverse end discs having outwardly offset central bosses to form seats for receiving the opposite ends of said barrel, said bosses having concentric co-axial apertures, a spindle tube engaging 20 in said apertures and connected to said discs for holding the latter in assembled position against the ends of said barrel, said discs having a plurality of spaced longitudinal flat lugs with their planes radially positioned relative to the axis of 25 said barrel struck inwardly from the body of said bosses, the edges of said lugs engaging said barrel, whereby said lugs will support the interior wall of said barrel against compressive forces.

4. In a winding spool, a tubular barrel, a pair 30 of transverse end heads, said heads comprising a pair of discs having outwardly offset bosses abutted against the ends of said barrel and a pair 35 of lining rings lying flat against the interior surfaces of said discs beyond the circumference of the barrel, said rings being snugly fitted over said barrel, said discs having a plurality of spaced longitudinal lugs struck inwardly from the body 40 of said disc with their edges engaging said barrel and having their planes radially positioned relative to the axis of said barrel so that the ends of said barrel will be securely held between said lining ring and said lugs.

5. In a winding spool, a tubular barrel, a pair 45 of transverse end plates secured at the ends of said barrel, said plates having longitudinal inwardly projecting flat lugs extending into the ends 50 of said barrel with their edges engaging said barrel, the planes of said lugs being in a radial position relative to the axis of said barrel so that the outer edge of said lugs will engage the interior surface of said barrel and support the edges thereof against collapse due to external compressive forces.
